UNITED STATES PATENT OFFICE.

HEINRICH BRUST, OF CASSEL, GERMANY.

PROJECTILE.

965,278.

Specification of Letters Patent. Patented July 26, 1910.

Application filed September 25, 1909. Serial No. 519,615.

To all whom it may concern:

Be it known that I, HEINRICH BRUST, a subject of the Emperor of Germany, residing at Cassel, Germany, have invented certain new and useful Improvements in Projectiles, of which the following is a specification.

In spite of the high development to which the construction of projectiles has attained, a projectile that is capable of inflicting serious damage to an armored battery, has not so far been invented. The shrapnels are unsuitable and the common shells are only effective after correct hits which, in the case of masked batteries, can only incidentally be relied on. Improvements in the shrapnels, with a view to make them more effective have not so far been successful.

The present invention relates to a projectile which will meet the requirements in that it involves the advantages of both shrapnels and common shells. The improved projectile is composed of a casing which is fitted on the outside with fin-like worms, adapted to rotate the projectile, during flight, round its longitudinal axis, and which is provided in its lower portion with a shrapnel charge and in its upper portion with a set of filling projectiles charged with a powerful explosive.

In the accompanying drawings the invention is illustrated, Figure 1 representing a central section through the charged projectile, Fig. 2, a central section through the empty casing, Fig. 3, a section of one of the filling projectiles, Fig. 4, a side view of the projectile showing its exterior worms, Fig. 5, a section of a filling projectile of another form of construction, Fig. 6, a sectional elevation of a projectile, showing a different way of loading the same, and Fig. 7, a section along line A—B of Fig. 6.

A casing *a*, with cylindrical bore, has a bottom chamber *b* adapted to receive the bursting charge for the shrapnel. The driving plate *c*, which is slightly arched, rests on a shoulder formed in the jacket and has a central aperture for the reception of the ignition tube. The latter is divided into two parts *d* and *e* which are separated by a pellet *f* of some slowly burning powder. The shrapnel charge *g* rests on the driving plate *c* and is covered by a disk *h* which is held by another shoulder in the jacket *a*. Above the disk *h* a propelling charge *i* is provided, the object of which is to drive out,

by means of a driving plate *k*, the filling projectiles *l* arranged on the latter. The projectile is closed by a suitable fuse capsule *m* which is held in the casing *a* by a weak screw-thread allowing it to disappear from the casing immediately the ignition takes place, so as to leave the passage clear for the filling projectiles.

To facilitate the loading of the casing, it is preferably composed of two parts screwed together, as shown in Fig. 2.

The casing *a* is fitted on the outside with fin-like worms *n*, fixed to the casing in any suitable manner. The resistance of the air on said worms, during the flight of the projectile, effects a rotation of the latter round its longitudinal axis. When the projectile is loaded in the gun, the spaces between the worms are filled with some fusible material, such as sulphur, resin, or the like, so as to give the projectile a firm bearing in the gun.

The elongated filling projectiles *l* consist of a shell provided on the nose with a percussion fuse *o* and at the base with a fuse *p*. The interior *q* of the shell is filled with an explosive of the most powerful nature, capable, when ignited by the percussion fuse *o*, through the projectile striking against any hard object, for instance a protective armor, of breaking such object into fragments. If not previously hitting any object, the projectile will, after a lapse of 2/10 second from the time of ignition of the charge *i*, *i. e.*, at a speed of 250 meters, after a flight of another 50 meters, be exploded by means of the fuse *p* which is ignited through the heat developed by the ignition of the charge *i*. The flash which ignites the charge *i* also ignites the pellet *f* which, after a lapse of 1/10 second, transmits the flash to the bottom chamber *b* which then effects a shattering of the shrapnel charge *g*. Through this interval between the explosions of the different charges, the projectiles *l* will have time to make way for the bullets of the shrapnel charge. The advantage of the improved projectile is, therefore, that it is capable, first of shattering the protections of a battery and then of directing the bullet charge against the occupants.

The chance of hitting the battery is increased by the number of filling projectiles employed.

When the elongated filling projectiles cannot be made to act satisfactorily, they may be substituted by spherical projectiles, as

shown in Fig. 5. Such projectiles have an explosive *r* in the center surrounded by a powder charge *s* adapted to burn about 2/10 second before igniting the explosive *r*. The 5 shell *t* consists of a glass body in which a chemical preparation is embedded, said preparation being adapted to ignite the powder charge *s* at *u*, when the glass breaks through the projectile striking against a 10 hard object, for instance an armor.

Figs. 6 and 7 show a different mode of loading the projectile. The elongated filling projectiles are here arranged in metal tubes *v*, out of which they are thrown by the propelling charges *i*. These tubes serve to direct the projectiles *l* and prevent them from 15 turning over during the flight.

I claim:—

1. A projectile, comprising in combination, a casing fitted on the outside with fin-like worms adapted to rotate the projectile during its flight, an ignition tube in the center of said casing, a shrapnel charge in the lower portion of said jacket, a set of 20 filling projectiles in the upper portion thereof, a propelling charge for driving out said filling projectiles, and a pellet of slowly burning powder in said ignition tube adapted to delay the ignition of the shrapnel 25 charge till the filling projectiles have been driven out, substantially as and for the purpose set forth.

2. A projectile, comprising in combination, a casing fitted on the outside with fin-like worms, a fusible material provided in the spaces between said worms, a bottom chamber adapted to receive a bursting charge, a driving plate arranged over said chamber and resting on a shoulder in the 35 casing, an ignition tube projecting through the center of said plate, shrapnel bullets arranged round the lower part of said tube, a disk covering said bullets and held by a shoulder in the casing, a propelling charge 40 disposed on said disk, a driving plate cover- 45

ing said propelling charge, a set of filling projectiles, charged with powerful explosive, adapted to be driven out of the casing by said propelling charge, and a pellet of slowly burning powder in said ignition tube between the bursting charges, adapted to delay the ignition of the bottom charge until the filling projectiles have been driven out, substantially as set forth. 50

3. A projectile, comprising in combination, a casing having in its lower portion a shrapnel charge and in its upper portion a set of filling projectiles charged with powerful explosive, a propelling charge adapted to drive out said projectiles, a bursting 60 charge adapted to disperse the shrapnel bullets, an ignition tube connecting both charges, and a pellet of slowly burning powder arranged in said tube between the charges and adapted to effect an ignition of 65 the bottom charge after the ignition of the upper one, substantially as and for the purpose set forth.

4. A projectile, comprising in combination, a casing having fin-like worms on its 70 exterior adapted to rotate the projectile during its flight, a shrapnel charge in the lower portion of said casing, filling projectiles in the upper portion of the same, a propelling charge adapted to drive out said projectiles, 75 a powerful explosive in said projectiles, a percussion fuse, fitted in the nose of each filling projectile, adapted to ignite the explosive through percussion, a time fuse in the base of each filling projectile adapted 80 to be ignited through the explosion of said propelling charge, and means for driving out said filling projectiles previous to the ignition of the shrapnel charge, substantially as and for the purpose set forth.

HEINRICH BRUST.
